UNITED STATES PATENT OFFICE

KURT SEIFERT AND ERNST SACHSE, OF MAGDEBURG, GERMANY

TICKET FILE

Application filed December 26, 1929, Serial No. 416,698, and in Germany January 9, 1929.

This invention relates to a ticket file with a protecting device covering the point of the filing pin. As compared with known ticket files of this type, the invention offers 5 the advantage of quick filing of the tickets and better protection of the point of the filing pin, the point being also protected when the ticket file is in use. The ticket file according to the invention is not much more 10 complicated than the ticket files with unprotected point.

The ticket file according to the invention consists of a vertical upwardly projecting filing pin, a horizontal arm extending over 15 the point of the filing pin, and of a clip oscillatably suspended on this horizontal arm the arms of which clip grip over the point of the filing pin.

An embodiment of the invention is illustrated by way of example in the accompanying drawings in which:

Fig. 1 shows the ticket file in perspective view,

Fig. 2 shows the file in use.

Fig. 3 shows the clip suspended on the horizontal arm.

Fig. 4 shows in top plan view the horizontal arm on which the clip is suspended.

Fig. 5 is a section on line 5—5 of Fig. 1.

Fig. 6 is a section through the protecting device on line 6—6 of Fig. 3.

Fig. 7 is a section on line 7—7 of Fig. 1.

A base plate 1 carries a vertical upwardly projecting filing pin 2 and a rod 3 also projecting vertically upwards. The upper end of rod 3 is bent at right angles and forms a horizontal arm 4. The cross section of the rod 3, 4 is preferably circular and flattened on both sides at a portion 5 of the horizontal arm 4. On the flattened portion a clamp 14 of a clip 6 is accommodated which is oscillatably mounted on a pin 7.

The clip 6 consists of two jaws 8 and 9 45 and of a back 10 connecting said two jaws; the back serves to limit the oscillating movement of the clip, the pivot point 7 of which is situated a certain distance in front of the extended central line of the filing needle. 50 The clip as shown on the drawing is obtained

by bending from a sheet metal blank stamped in lyre-shape.

The cross section of back 10 is shown in Fig. 7. This cross section has been selected in order that at pressure exerted by the hand obliquely from the front upon the clip or at a pressure upon a side face of the clip and further at pressure from the rear upon the clip oscillating of the clip is prevented. The clip has always so much play in lateral direction or is sufficiently resilient so that, when a pressure from the side is exerted upon the clip, the filling needle engages with one of the pockets 16.

The edge 11 of each of the two plates 8 and 9, which comes into contact with the tickets 12 to be filed, is rounded off.

Before spiking a ticket on the filing pin 2, the clip 6 is oscillated by the ticket 12 until the point of the pin 2 is exposed. It is not necessary to oscillate the clip by hand, even when a ticket has to be removed from the filing pin. The ticket, when being lifted, presses the clip aside, owing to its curved edges 11, until the point of the filing pin 2 is exposed.

If it is desired to remove a larger number of tickets, it is advisable to bring the clip 6 into the position shown in Fig. 3. For this purpose a handle 13 and a clamp 14 are provided. The clamp is made of spring wire and consequently, when pressure is exerted on the handle 13, springs over the flattened cheeks of the horizontal arm 4 so that the clip is hooked onto the horizontal arm. If a slight pressure is exerted on the clamp, the clip again drops and covers the point of the filing pin 2. The plates 8 and 9 have each a bulged out portion 15 at the point designed to engage over the filing pin so that this pin 2 catches the clip also when a pressure is exerted on one of its sides (8 or 9).

The protecting of the pin point is not only effected by the clip 6, but also by the rod 3, 4. It is immaterial, from which side the hand is approached, an obstacle is always encountered and consequently it is impossible to place the hand on the point of the pin.

The clip may also be of other shape than shown in the drawing, provided it is shaped 100

in such a manner that the filing pin engages with the oscillatable clip and the clip can be automatically pushed back by the tickets to be filed. In the form of construction shown, 5 the clip is shaped so that it can be also automatically pushed back by the tickets being removed.

It is also possible to suspend the ticket file. In this instance a suspension plate is 10 used instead of the base plate. From this suspension plate a horizontal arm 4 projects for carrying the clip 6. The filing pin 2 projects from the suspension plate in the same plane as the horizontal arm 4 and is 15 brought by suitably bending vertically under the clip.

We claim:

1. A ticket file, comprising in combination an upwardly projecting filing pin, a vertical 20 rod at some distance from said filing pin bent at the upper end to form a horizontal arm extending above the point of the filing pin, and a clip composed of two plates, oscillatably suspended from said horizontal arm 25 adapted to cover the point of said filing pin.

2. A ticket file, comprising in combination an upwardly projecting filing pin, a vertical rod at some distance from said filing pin bent at the upper end to form a horizontal arm 30 above the point of said filing pin, and a clip oscillatably suspended on said horizontal arm at a distance in front of the extended centre axis of said filing pin, said clip composed of two plates, a back connecting said two plates 35 the one with the other forming a stop adapted to bear against the side of said pin situated between said plates and thereby preventing said clip oscillating towards one side.

3. A ticket file, comprising in combination 40 an upwardly projecting filing pin, a vertical rod at some distance from said filing pin bent at the upper end to form a horizontal arm extending over the point of said filing pin, a clip suspended on said horizontal arm 45 at a distance in front of the axis of said filing pin said clip composed of two plates curved at the lower edges and a back connecting said two plates adapted to bear against the side of 50 said filing pin when said clip is in the covering position.

4. A ticket file, comprising in combination 45 an upwardly projecting filing pin, a vertical rod at some distance from said filing pin bent at the upper end to form a horizontal arm extending above the point of said filing pin, a clip suspended on said horizontal arm at a distance in front of the extended axis of said filing pin said clip composed of two plates 55 with outer edges curved adapted to be engaged by the tickets as they are filed to deflect the clip, a back plate connecting said two plates adapted to limit the oscillating movement of said clip in bearing in the covering 60 position against the point of said filing pin, a handle on said clip, and a clamp on said

clip adapted to hold said clip in raised position.

5. A ticket file, comprising in combination an upwardly projecting filing pin, a vertical rod at some distance from said filing pin bent at the upper end to form a horizontal arm extending above the point of said filing pin, a clip suspended on said horizontal arm at a distance in front of the axis of said filing pin said clip composed of two plates having each an outwardly bulged portion, and a back connecting said plates and adapted to limit the oscillating movement of said clip, a portion of the outer edges of said plates curved and adapted to be engaged by the tickets as they are filed to deflect the clip, a handle for oscillating said clip, and a clamp for holding said clip in raised position.

In testimony whereof we affix our signatures.

Dr. KURT SEIFERT.
ERNST SACHSE.
